UNITED STATES PATENT OFFICE.

EDWARD S. LYONS, OF WOBURN, MASSACHUSETTS.

GRINDING-MACHINE.

1,223,500.

Specification of Letters Patent. Patented Apr. 24, 1917.

Application filed September 23, 1916. Serial No. 121,872.

To all whom it may concern:

Be it known that I, EDWARD S. LYONS, a citizen of the United States, residing at Woburn, county of Middlesex, State of Massachusetts, have invented an Improvement in Grinding-Machines, of which the following description, in connection with the accompanying drawing, is a specification, like characters on the drawing representing like parts.

This invention relates to improvements in grinding machines and particularly grinding mechanism for maintaining a sharp edge upon traveling knives or cutters for leather splitting machines or similar devices.

The object of the invention is to provide means for supporting a rotatable grinding member in such a manner that the said grinding member may be rotated freely without vibration and thereby enabling it to produce a smooth uniform edge upon the cutter. Another object of the invention is to provide a novel and efficient anti-friction bearing for the shaft supporting the rotatable grinding member which can be readily adjusted to take up wear and may be constantly supplied with lubricant.

Other features of the invention will be fully set forth in the accompanying description and accompanying drawings and will be particularly pointed out in the annexed claims.

The drawings illustrate in diagrammatic form the application of my invention to grinding mechanism for sharpening an endless cutter such as is used in leather splitting machines.

Figure 1 is a front elevation of the rotatable grinding members operating upon the edge of an endless knife or cutter and showing in section the improved supporting bearings for the shafts of the grinders;

Fig. 2 is a detail side elevation showing the position of the grinding members relatively to the edge of the cutter which is being sharpened.

In all classes of grinding machines embodying a rotating grinding member it is desirable that the grinding member shall run true so that chattering and consequently irregular grinding of the blade will be avoided.

In machines such as leather splitting machines in which an endless traveling cutter severs the leather or hide into thin slices it is very essential that a uniform sharp edge

shall be maintained upon the cutter. In order to accomplish this purpose leather splitting machines are usually provided with a pair of grinding wheels or disks which are supported beneath the bed of the machine and are adapted to be so positioned as to engage and grind the knife as its lower lead passes by the grinder. Heretofore such grinders have been supported upon shafts journaled in bearings in brackets supported from the main frame of the machine. Ordinarily the ends of the shafts for grinders are tapered and seated in correspondingly tapered sockets in studs which may be adjusted in the direction of the axis of the shaft to form a sufficiently tight bearing to prevent vibration of the grinders. A great amount of difficulty, however, is encountered in the use of such bearings. They are necessarily difficult to adjust and if the bearing is made too tight it will heat and thereby expand the bearing members so as to bind or "set" the shaft of the grinder thus retarding or preventing its rotation. If the bearings are not adjusted tightly enough the wheel will vibrate and produce an irregular or corrugated edge upon the cutter which of course will improperly slice the leather.

In other machines adapted for similar uses the imperfect grinding of the cutter causes a resulting imperfect product and the above application of my invention is referred to merely as illustrative of one of its important uses. In the preferred embodiment of the invention illustrated herein two grinding members in the form of grinding disks are shown as engaging a section of an endless knife. These grinding members are supported upon similar shafts having similar bearings, and a description of one will therefore be sufficient. The grinding members 1, 2 are each preferably in the form of grinding disks or cylinders rigidly secured

upon shafts 3, 4 which are supported at their ends upon adjustable cup and cone bearings. The shaft for each of the grinders comprise a central cylindrical portion 5 having a screw-threaded section 6 and an enlarged section 7 presenting a shoulder 8 adapted to engage the end of the clamping disk 9 which engages one face of the grinder 1. The opposite side of the grinder is engaged by a similar clamping disk 10 which is forced firmly against the grinder by a nut 11 screwed upon the threaded section 6 of the shaft thereby forcing the grinder and

its clamping collars 9 and 10 firmly against the shoulder 8 of the enlarged portion 7 so that the grinder is rigidly affixed to the shaft.

5 The shafts 3 and 4 desirably are provided with pulleys 12 and 13 by means of which rotation may be imparted to said shafts. The ends of the shafts 3, 4 are provided with reduced screw-threaded end portions 14, 15 which present shoulders 16, 17 adapted to limit the movement of cup members 18, 19 having raceways 20, 21 for series of anti-friction instrumentalities such as balls 22, 23. The coöperating bearing members for the ends of the shaft preferably comprise studs 24, 25 which are adjustably seated in the brackets 26, 27 integral with or carried by the frame of the machine (not shown). The studs 24, 25 are provided with conoidal ends 28, 29 adapted to engage respectively the balls 22, 23 in the raceways 20, 21 of the cup members. The studs 24, 25 are longitudinally movable in the direction of the axis of the shafts 3, 4 and may be locked in adjusted position by set screws 30, 31 passing through the brackets 26, 27 and engaging at their ends the studs 24, 25.

The studs 24, 25 desirably are bored axially to provide oil ducts 32 leading to the bearings between the cup and cone. The outer portion of each stud is also preferably countersunk to provide a chamber 33 adapted to contain a body of lubricant, and the walls of such chamber are screw-threaded 35 to receive a screw-threaded plug 34 having a transverse slot 35 by means of which it may be rotated and advanced into or removed from said chamber. The chamber 33 and duct 32 thus provided with the adjustable plug 34 form a "grease gun" by means of which a proper amount of lubricant may always be supplied to the bearings. Suitable caps 36 preferably of stamped sheet metal fitted upon the ends of the bearing cups 45 serve to retain the lubricant in the bearings and also effectively to exclude dust therefrom.

As illustrated herein the supporting mechanism for the grinders 1 and 2 is so arranged that the periphery of said grinders shall be in different vertical planes and overlapping a short distance as illustrated in Fig. 2 so that both sides of the edge of the blade B passing between them will be simultaneously ground. While as illustrated in the drawing the studs 24, 25 are supported in brackets 26, 27 carried by the frame (not shown) it will be obvious that other supporting means may be provided and that 55 a single grinder and grinding shaft may be utilized for some kinds of grinding instead of the pair of coöperating grinding mecha-

nisms illustrated herein. It is also to be understood that the particular mechanisms disclosed herein are illustrative in character 65 and not restrictive within the meaning and scope of the following claims.

Having thus fully described my invention, what I claim as new and desire to secure by Letters Patent is:

70 1. A grinding machine comprising a rotatable grinding member rigidly secured upon a shaft, cups containing raceways for rotatable antifriction elements secured upon the ends of said shaft, means for preventing movement of said cups longitudinally of said shaft, coöperating conoidal bearing members engaging said antifriction instrumentalities and means for adjusting said conoidal members in the direction of the axis 75 of said shaft.

2. A grinding machine comprising a rotatable grinding member rigidly secured upon a shaft having reduced screw-threaded end portions and presenting shoulders, cups 80 containing raceways for rotatable anti-friction elements screwed upon the ends of said shaft and against said shoulders, coöperating conoidal bearing members engaging said anti-friction instrumentalities, and means for adjusting said conoidal members in the direction of the axis 85 of the shaft.

3. A grinding machine comprising a rotatable grinding member rigidly secured upon the shaft, means for supporting the 95 said shaft including a cup containing a raceway for rotatable anti-friction elements secured to the end of said shaft, a coöperating conical bearing member engaging said anti-friction instrumentalities, said conical 100 bearing member being provided with a lubricating chamber, and a duct leading therefrom to said bearing, and means for forcing lubricant from said chamber through said duct into the bearing.

105 4. A grinding machine comprising a rotatable grinding member rigidly secured upon the shaft, means for supporting the said shaft including a cup containing a raceway for rotatable anti-friction elements secured to the end of said shaft, a coöperating conical bearing member engaging said anti-friction instrumentalities, said conical bearing member being provided with a lubricating chamber having a screw-threaded 110 wall, a duct leading from said chamber to said bearing, and a plug having a screw-threaded periphery engaging the screw-threads of the walls of said chamber and adapted to be advanced to force lubricant 115 through said duct into said bearing.

120 In testimony whereof, I have signed my name to this specification.

EDWARD S. LYONS.
